US0D1017910S

(12) **United States Design Patent** (10) **Patent No.:** **US D1,017,910 S**
(45) **Date of Patent:** **** Mar. 12, 2024**

(54) **WEARABLE PHYSICAL SHIELD**

- (71) Applicant: **LSI Solutions, Inc.**, Victor, NY (US)
(72) Inventor: **Jude S. Sauer**, Pittsford, NY (US)
(73) Assignee: **LSI Solutions, Inc.**, Victor, NY (US)
(**) Term: **15 Years**
(21) Appl. No.: **29/796,936**
(22) Filed: **Jun. 28, 2021**

Related U.S. Application Data

Primary Examiner — Kimberly Barnes

(74) *Attorney, Agent, or Firm* — Michael E. Coyne

(57) **CLAIM**

The ornamental design for a wearable physical shield, substantially as shown and described.

DESCRIPTION

FIG. 1 is an image of a front perspective view of a wearable physical shield showing my new design;
FIG. 2 is an image of a front view thereof;
FIG. 3 is an image of a rear view thereof;
FIG. 4 is an image of a left side view thereof;
FIG. 5 is an image of a right side view thereof;
FIG. 6 is an image of a top view thereof;
FIG. 7 is an image of a bottom view thereof; and,
FIG. 8 is an image of a rear perspective view thereof.
The broken lines in the drawings depict portions of the wearable physical shield that form no part of the claimed design.

1 Claim, 8 Drawing Sheets
